UNITED STATES PATENT OFFICE.

EDWARD CLAUDE LEACHMAN, OF BAYSWATER, LONDON, ENGLAND.

ADVERTISING DEVICE.

1,366,322.

Specification of Letters Patent. Patented Jan. 18, 1921.

Application filed April 1, 1920. Serial No. 370,530.

To all whom it may concern:

Be it known that I, EDWARD CLAUDE LEACHMAN, a subject of the King of England, residing in Bayswater, London, England, have invented certain new and useful Improvements in Advertising Devices, of which the following is a specification.

This invention is for improvements in or relating to advertising devices, and has for 10 its main object to provide a construction which shall be particularly suitable for use, say in the foyer of a cinematograph theater, to advertise the items of program in a particularly pleasing and artistic manner.

15 Another object is to provide an advertising device in which an advertisement made up of separate letters suspended in front of an illuminated picture can be very readily removed or replaced by another advertisement set up in the same manner.

20 The type of advertising device to which this invention relates is that in which the advertising matter, such as legends composed of opaque letters, is arranged on a transparent support comprising two or more strips of transparent material arranged edge to edge one above the other in front of an illuminating device and having their edges spaced apart.

25 A construction of advertising device of the above type has heretofore been proposed wherein a transparent, translucent sheet or screen was arranged between the transparent support and the illuminating device.

30 According to the main feature of this invention in an advertising device of the type described there is interposed between the illuminating device and the transparent support a pictorial screen wholly or partly translucent.

35 Conveniently, the strips which make up the transparent support are separated at their adjacent edges by distance-pieces each of a thickness only slightly greater than the 40 thickness of the suspension portion of a legend inserted between the strips.

45 A diffusing device of textile material, for example a sheet of plain tracing cloth, or plain linen or other cloth, may be arranged 50 between the illuminating device and the pictorial screen.

The invention is illustrated by way of example in the accompanying drawing, wherein—

55 Figure 1 is a front elevation showing one form of advertising device according to the

invention, whereof parts are shown broken away;

Fig. 2 is a vertical section taken on the line 2—2 in Fig. 1, and

Fig. 3 is an enlarged sectional view of a detail.

Like reference letters designate like parts throughout the several views.

Referring to the drawing, the advertising device comprises a rectangular sheet-metal casing A having rabbets formed in it as shown at A¹ and A², a rectangular carrier B which is fitted into the inner rabbet A² and is retained therein at the bottom by lugs A³, and a frame C carrying a sheet of glass C¹, which is fitted into the rabbet A¹. This frame C which may conveniently be of an ornamental character is readily detachably attached to the casing A at one side by a pin that extends through a slot A⁴ in the casing A, and to the other side by a fastening device C² of any convenient kind, so that the frame C can be easily removed bodily away from the carrier B. If desired 80 the frame C may be hinged at one side to the casing A and locked thereto at the other side. At the back of the carrier B within the casing A is arranged an illuminating device comprising electric lamps D placed 85 in front of mirrors or reflectors E which may be of any convenient kind.

The carrier B which may be of sheet-metal is intended to be more or less vertical when in use, and its two sides are formed 90 with rabbets or ledges B¹ on which rest strips F of a transparent material, preferably plate glass. These glass strips are retained in place in the carrier by strips of sheet metal F¹ which are screwed to the 95 front face of the carrier and project over the ends of the strips of glass. When the advertising device is in place, the adjacent edges of the glass strips F will lie more or less horizontal, but they are prevented from 110 resting one on another by distance-pieces F², for example of aluminium, placed between them at their ends. In the device illustrated these distance-pieces are in the form of a T with the down-stroke portion 105 inserted between the glass strips.

Advertising matter in the form of legends or signs G are mounted upon some or all of these strips F except the top one, conveniently one legend to each strip, while the 110 top strip may have painted on it or otherwise applied to it a notice H or an advertise-

ment preferably relating to the legends below it. By releasing the top screws in the retaining strips of metal F^1 the top strip of glass, which bears for example a notice 5 "Now showing," can be readily removed and exchanged for another glass strip bearing another notice, for example "Next week."

Each legend G is made up of separate 10 letters or signs of metal or other opaque material, bent or otherwise provided with a lug G^1 disposed at an angle to the letter or sign and arranged to hang upon an upper edge of one of the strips, as clearly 15 shown in Fig. 3. The thickness of each distance-piece F^2 is only slightly greater than the effective thickness of the lugs, so that the letters can be very readily hung on the strips by simply entering the lugs 20 between the adjacent edges of any two strips. If the carrier B is hung vertically or slanting backward, no means are required for securing the letters in position, while if the carrier slants forward the letters 25 will be retained in place by the glass C^1 .

Between the strips F and the illuminating device D , E is arranged an artistic pictorial screen J which is carried on the front of a rectangular wooden frame K 30 mounted in the rabbet A^2 in the casing behind the carrier B . This screen J is wholly or partly translucent and consists of a picture painted, printed, or otherwise reproduced upon a sheet of tracing cloth. At the 35 back of the frame K there may be provided a light-diffusing device L which is shown as a sheet of plain tracing-cloth but it may be a sheet of plain linen or other cloth. This sheet L operates to prevent direct light 40 from the lamps D reaching the pictorial screen and the glass strips F .

The illuminating device may include apparatus for producing in succession different combinations of colored lights in order 45 to produce varying effects upon the pictorial screen and to attract attention to the advertising matter. The letters forming the legends being opaque and being situated in front of the pictorial screen, show up 50 very clearly against the latter, when the device is in use, while the fact that the transparent support for these legends is composed of a number of strips passes almost unnoticed since the narrow gaps between 55 these strips are scarcely visible near to the device, and are almost or quite invisible to a person situated a few yards away therefrom when the illuminating device is lighted up.

60 When it is desired to change the legends it is only necessary to move the glazed frame C away from the carrier B to expose the letters, whereupon these can be very readily removed from their supports and 65 other legends suspended in their stead. If

it is wished to change the notice H , then the top strip F must be removed from the carrier B and another strip provided with a different notice inserted in its place. As the strips F^1 are flexible this change can be 70 made very readily after removing two screws.

The described advertising device has a very attractive and artistic appearance and is particularly adapted for advertising a 75 cinematograph program. In this case each of the legends G is the title of a film, and the top glass strip F may have painted on it a notice such as "Now showing" or "To-day." It is to be understood, however, 80 that the advertising device may be put to uses other than the announcement of cinema and other programs, since it is readily applicable to any circumstances in which it is desired to combine the advantage of being able to change the legends easily with that of providing a really artistic effect. 85

What I claim as my invention and desire to secure by Letters Patent is:—

1. In an advertising device, the combination with an illuminating device, a transparent support comprising at least two strips of transparent material arranged edge-to-edge one above another in front of said illuminating device and having their adjacent edges spaced apart, and advertising matter suspended in spaced relation from an upper edge of at least one strip below the top one, of a pictorial screen that is at least partly translucent interposed between 95 said illuminating device and said transparent support, and visible simultaneously with said advertising matter, substantially as set forth.

2. In an advertising device, the combination with an illuminating device, a transparent support comprising at least two strips of transparent material arranged edge-to-edge one above another in front of said illuminating device, and having their adjacent edges spaced apart, and advertising matter suspended in spaced relation from the upper edge of at least one strip below the top one, of a translucent pictorial screen 100 interposed between said illuminating device and said transparent support, and visible in combination with said advertising matter, 105 and a diffusing screen of textile material interposed between said illuminating device and said pictorial screen, substantially as set 110 forth.

3. An advertising device comprising in combination an illuminating device, a transparent support comprising at least two strips of transparent material arranged edge-to-edge one above another in front of said illuminating device, distance-pieces between the adjacent edges of said strips, advertising matter comprising opaque letters having each a thin lug inserted into the gap between 115 120 125 130

- two adjacent strips and readily detachably suspended thereby at the front of said transparent support, the thickness of each of which distance-pieces is only slightly greater than the thickness of a lug, and a pictorial screen that is at least partly translucent interposed between said illuminating device and said transparent support, and visible in combination with said letters substantially as set forth. 5
4. An advertising device comprising in combination an illuminating device, a transparent support comprising at least two strips of transparent material arranged edge-to-edge one above another in front of said illuminating device, distance-pieces between the adjacent edges of said strips, advertising matter comprising opaque letters having each a thin lug inserted into a gap between two adjacent strips and readily detachably suspended thereby on the front of said transparent support, the thickness of each of which distance-pieces is only slightly greater than the thickness of a lug, and a glazed frame detachably mounted on said casing with its glass situated just in front of said advertising matter. 50
5. An advertising device comprising a casing, means for illuminating the interior of said casing, a pictorial screen that is at least partly translucent extending across one side of said casing, a plurality of transparent supports, and an opaque letter removably mounted on one of said transparent supports to appear in contrast in combination with said screen when the casing is illuminated, substantially as set forth. 55
6. An advertising device, comprising a casing, means for illuminating the interior of said casing, a pictorial screen that is at least partly translucent extending across one side of said casing, a plurality of transparent supports, and an opaque letter removably mounted on one of said transparent supports to appear in contrast in combination with said screen when the casing is illuminated, substantially as set forth. 60
7. An advertising device, comprising a casing, means for illuminating the entire interior of said casing simultaneously, a pictorial screen that is at least partly translucent extending across one side of said casing, a plurality of transparent supports, and a plurality of opaque letters removably mounted on at least one of said supports to appear in contrast in combination with said screen when the casing is illuminated, substantially as set forth. 65
8. An advertising device, comprising a casing, means for illuminating the interior of said casing, a pictorial screen that is at least partly translucent extending across one side of said casing, a plurality of transparent supports having their adjacent edges in spaced relation, and an opaque letter removably suspended from the edge of one of said supports to appear in contrast in combination with said screen when the casing is illuminated, substantially as set forth. 70
9. An advertising device comprising a casing, means for illuminating the interior of said casing, a pictorial screen that is at least partly translucent extending across one side of said casing, a plurality of transparent supports, and an opaque letter removably mounted on one of said transparent supports to appear in contrast in combination with said screen when the casing is illuminated, substantially as set forth. 75
10. An advertising device comprising in combination a casing, an illuminating device mounted in the same at the rear thereof, a diffusing screen of textile material detachably mounted in said casing in front of said illuminating device, a translucent pictorial screen detachably mounted in said casing in front of said diffusing screen, a transparent support comprising at least two strips of transparent material removably arranged in said casing one above another edge-to-edge in front of said pictorial screen, distance-pieces separating the adjacent edges of said

In testimony whereof I affix my signature.

EDWARD CLAUDE LEACHMAN.
